UNITED STATES PATENT OFFICE.

RUSSELL Y. MCINTYRE, OF NEWMAN, ILLINOIS, ASSIGNOR OF ONE-HALF TO JAMES D. MCINTYRE, OF NEWMAN, ILLINOIS.

CARRIER-SLING.

1,184,190.

Specification of Letters Patent.

Patented May 23, 1916.

Application filed April 23, 1915. Serial No. 23,359.

To all whom it may concern:

Be it known that I, RUSSELL Y. MCINTYRE, a citizen of the United States, and a resident of the town of Newman, county of Douglas, and State of Illinois, have invented certain new and useful Improvements in Carrier-Slings, of which the following is a specification.

My invention relates to improvements in carrier slings such as are used in the hauling of bales of hay, cotton and the like, and has for its object the production of a sling of this character which will be of improved construction and efficient in operation.

A further object is the production of a sling which will be adapted to automatically tighten itself about the load carried thereby.

Other objects will appear hereinafter.

With these objects in view, the invention consists in the combinations and arrangements of parts hereinafter described and claimed.

The invention will be best understood by reference to the accompanying drawing forming a part of this specification, and in which,

Figure 1 is a side elevation of a carrier sling embodying the invention, the bight portion of the sling proper being omitted, Fig. 2 is a front elevation of the construction shown in Fig. 1, Fig. 3 is a side elevation of a carrier sling of slightly modified form, and Fig. 4 is a front elevation of the upper end portion of the construction shown in Fig. 3.

One form of construction, as illustrated in the drawing, comprises a chain 1 or sling proper which is connected at its upper end with an eye 2 through the medium of which the sling may be connected with the usual depending hook of a conventional carrier. Loosely slidable upon the chain 1 is a sleeve 3 upon one side of which is arranged a finger 4 pivotally secured at 5 between outwardly projecting ears 6 formed upon a plate 7 which is secured rigidly to sleeve 3. Finger 4 is adapted for engagement with the outer end of the chain 1, the terminal link of the chain being adapted for engagement over said finger, as clearly shown in Fig. 1.

The finger 4 is held in operative position by means of a detent 8 having a bifurcated rearward end which is fulcrumed at 9 to the sleeve 3. The arrangement is such, as will be seen, that the detent 8 is adapted to en-

gage over the upper or free end of the finger 4, being held in operative relation therewith through friction, in order to hold said finger in operative position. Upon release of said finger, the same is adapted to rock downwardly by gravity and under the influence of the chain end engaging therewith, in order to release said chain end so as to drop the load supported by the sling. The detent 8 is rocked upwardly to releasing position by means of a trip rope 10 which is connected at one end with the outer end of said detent, said rope projecting upwardly over a channel pulley 11 mounted in the eye 2, as shown.

With the construction set forth, it will be seen that the sleeve 3 is free for sliding along the chain 1 with the result that, when the sling is engaged with a load, said sleeve 3 will slide along the chain under the influence of the outer end of the chain which is connected therewith and thus effect, automatically, the tightening of the sling about the load. This will, of course, prevent accidental slipping of the load from the sling since, with the construction set forth, the heavier the load the more secure will be the engagement thereof by the sling. Also, with the arrangement disclosed, after the detent 8 has been tripped by the rope 10 to release the sling, said rope will serve as a means of pulling the sling back for engagement with a second load, thus avoiding the necessity of the provision of a second rope for this purpose.

The construction shown in Figs. 3 and 4 is identical to that shown in Figs. 1 and 2, except that in this form of the device an eye 2' is provided for engagement with the sling chain 1 which is not equipped with a channel pulley 11 for engagement with the trip rope 10. In lieu of this construction, however, the eye 2' is formed with a semi-circular depression or recess 12 for engagement with the rope, as clearly shown in Fig. 4.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. A carrier sling comprising a flexible element; a member at one end of said element for connecting the same to a support; a sleeve loosely slideable on said element; a finger pivotally mounted on said sleeve for releasably connecting the opposite end of said flexible element thereto; a detent for releasably holding said finger in operative position and adapted to be rocked upwardly to release said finger; and a trip rope operatively connected with said detent, said connecting member having an opening at its upper end for engagement with a support and for guiding said trip rope, substantially as described.
2. A carrier sling comprising a flexible element; a member at one end of said element for connecting the same to a support;

a sleeve loosely slideable on said element; a finger pivotally mounted on said sleeve for releasably connecting the opposite end of said flexible element thereto; a detent for releasably holding said finger in operative position and adapted to be rocked upwardly to release said finger; a trip rope operatively connected with said detent, said connecting member having an opening in its upper end for engagement with a support and for guiding said trip rope; and a channel in the lower portion of said opening for engagement with said trip rope, substantially as described.

In testimony whereof I have signed my name to this specification in the presence of two subscribing witnesses.

RUSSELL Y. McINTYRE.
